UNITED STATES PATENT OFFICE.

MERLE J. WIGHTMAN, OF WEST NEW BRIGHTON, NEW YORK, ASSIGNOR TO DOMESTIC STOKER COMPANY, OF NEW YORK, N. Y., A CORPORATION OF DELAWARE.

UNDERFEED STOKER.

Application filed March 26, 1926. Serial No. 97,538.

This invention relates to underfeed stokers for use particularly in domestic furnaces, and consists of an improvement in the invention described in my prior Patent No. 1,454, 5 697, May 8, 1923.

The underfeed stoker of my prior patent involves a fire pot into which the fuel, such for example as bituminous or other finely comminuted coal, is fed from the bottom, 10 and a constantly rotating device for rotating the fuel within the fire pot. To minimize friction this rotating device is mounted on ball bearings.

The structure described in my patent operates satisfactorily under some conditions. 15 But under other conditions trouble has been experienced due to dust clogging up the ball bearings upon which the rotary device is mounted.

20 The primary object of my present invention is to provide means for automatically cleaning and keeping clean the ball race in which the ball bearings are located.

Other and further objects of my invention will appear more fully hereinafter.

In the accompanying drawings, Fig. 1 is a vertical section of an underfeed device embodying my invention, and Fig. 2 is a plan view taken on the line 2—2 of Fig. 1.

30 I shall preface my description of the invention to which this application is particularly directed, by a brief description of the underfeed device to which I have applied that invention.

35 As illustrated in the drawing, this device includes a fire pot 11 and means, such as the screw conveyer 12, for feeding fuel into that fire pot from the bottom. Jets 13 supplied with air under pressure through the concentric conduit 14, provide the necessary amount of forced draft for satisfactory combustion.

In burners of this type, when bituminous coal is used, it is found necessary to provide some means for agitating the bed to prevent 45 excessive clinkering. The means shown in the drawing for accomplishing this function consists of the rotary stirrer 15. This stirrer, as shown, is preferably provided with a plurality of vertical stirring rods 16 which lie 50 within the coal bed in the fire pot, and upon rotation of the stirrer agitate the fuel sufficiently to avoid the formation of clinkers. The upper section of the fire pot, as shown, is provided with helical screw threads which 55 have for their function the depression of

ignited pieces of fuel to assist in the combustion.

Any suitable means may be provided for rotating the stirrer 15, as for example the gears 17, 18, 19 and 20. To minimize the power required for rotating the stirrer it is 60 preferably mounted upon ball bearings 21 mounted in the ball race 22.

As described up to this point the structure shown in the accompanying drawings 65 involves nothing novel as compared with the disclosure of my aforesaid patent.

As previously indicated, it has been found on occasions that difficulty is experienced in the operation of the structure of my patent 70 by reason of the fact that coal dust which is present in large quantities is apt to find its way into the ball race designated in my present drawings as 22, and thus interfere with the rotation of the stirrer. My present 75 invention has to do primarily with the avoidance of this difficulty.

The means which I have provided for accomplishing this purpose are best shown in Fig. 2 of the drawings. On reference to that figure it will be seen that instead of filling the ball race completely with ball bearings I have inserted into the race at several points, cleaning devices 23. These devices may take various forms, but as illustrated 80 in the drawings they consist of headless screw studs which have been found to be particularly efficient because of the sharp edges produced by their threading. As shown in the drawings, I have inserted four 85 of these devices, but of course the particular number is not important except that sufficient should be provided to accomplish the desired result.

The operation of these cleaning devices is 90 doubtless understood from the above description. As the machine operates the balls travel about the race and in doing so cause the cleaning devices to travel with them. These cleaning devices being of sufficient 95 size to fill the ball race almost completely, scrape up whatever dust reaches the race and force it out through the channel 24 formed between the two members into which the race is cut. In this way the race is 100 kept substantially free from coal dust and other foreign particles and interference with the operation of the ball bearing support for the stirrer is thus avoided.

105 The terms and expressions which I have 110

employed are used as terms of description and not of limitation, and I have no intention, in the use of such terms and expressions, of excluding any mechanical equivalent of the features shown and described, or portions thereof, but recognize that various modifications are possible within the scope of the invention claimed.

What I claim is:

- 10 1. In a stoker, a rotating stirring member, a ball bearing support for said member including a ball race and balls, and means other than the balls located in said race for removing therefrom coal dust and other foreign particles.
- 15 2. In a stoker, a rotating stirring member, a ball bearing support for said member including a ball race and balls, and a plurality

of headless screw studs located in said race for removing therefrom coal dust and other 20 foreign particles.

3. In a ball bearing device particularly adapted for use in underfeed stoker apparatus, a dust clearing member having the edge portions arranged to engage and substantially fit the curved walls of a ball raceway groove, said member being adapted to move along the groove to clear obstructions therefrom.

4. In a ball bearing, a groove clearing device comprising a scraper member adapted to be placed in a raceway groove between adjacent balls, said scraper member being arranged to move along the groove under the impelling action of the moving balls.

MERLE J. WIGHTMAN.
